UNITED STATES PATENT OFFICE

CHARLES E. SAYRE, OF LAUREL, MONTANA

GROUND PACKER

Application filed October 23, 1928. Serial No. 314,337.

The present invention relates generally to an agricultural apparatus and particularly to a ground packer and has for its prime object to provide an apparatus of this nature comprising a plurality of connected sections, each section including a plurality of blades which may be adjusted.

A further very important object of the invention resides in the provision of an apparatus of this nature which is exceedingly simple in its construction, strong and durable, inexpensive to manufacture, easy to adjust and thoroughly efficient and reliable in use and operation.

15 With the above and numerous other objects in view as will appear as the description proceeds, the invention resides in certain novel features of construction, and in the combination and arrangement of parts as will be 20 hereinafter more fully described and claimed.

In the drawing:

Figure 1 is a top plan view of the apparatus embodying the features of my invention,

Figure 2 is an enlarged detail side elevation of the front end of the apparatus,

Figure 3 is an enlarged detail section through one section of the apparatus,

Figure 4 is a sectional view taken substantially on the line 4—4 of Figure 3, and

30 Figure 5 is a top plan view of one of the packer blades attached to its shaft.

Referring to the drawing in detail it will be seen that the numeral 5 denotes a transversely disposed draw bar at the front end of the apparatus which is provided with a plurality of hook bolts 6 extending rearwardly therefrom.

Two rows of sections extend rearwardly from the draw bar 5 and each section comprises a U-shaped hood 7 of elongated construction with the bight portions disposed forwardly and the upper leg slightly wider than the lower leg as is clearly illustrated in Figure 3. Bearing blocks 8 are mounted

45 in the ends of the hood 7. Notched segments 9 are mounted on the upper legs at the ends of the hoods by means of screws 10 which also hold the blocks 8 in place.

Screws 11 are used to fasten the blocks to 50 the bottom leg of the hood. A shaft 12 is

rockable in the blocks 8 and have levers 14 secured to the ends thereof and rising therefrom. Hook plates 15 are fixed in the ends of the hood to the outer sides of the block and have eyes 16 at their forward ends and hooks 55 17 at their rear ends.

Links 18 are engaged in the eyes 16 and are adapted to engage hooks 17 except the two forwardmost sections and their links engage the hooks 6. U-shaped members 19 are fixed 60 by means of rivets 20 or the like circumjacent the shaft 12 and the ends terminate rearwardly thereof and have brackets 22 rockable therebetween by pins 23.

Packer blades 24 are anchored by means 65 of bolts 25 in the brackets 22. Obviously by rocking the levers 14 the packer blades may be swung upwardly or downwardly to adjust their digging depth. Detent structures 26 are mounted on the levers 14 for cooperation 70 with the notched segments 9 so as to hold the packer blades in different adjusted positions. This packing apparatus works on a swivel which always pulls straight through the ground. 75

The packer blades work at an adjustable depth in the ground. This apparatus cuts the air spaces out of the ground, pulverizes and packs the ground in one operation and thereby retains the moisture and keeps the 80 roots of the grain in good growing condition to cause an increased yield.

It is thought that the construction, utility, operation and advantages of this invention will now be quite apparent to those skilled in 85 this art without a more detailed description thereof.

The present embodiment of the invention has been disclosed in considerable detail merely for the purposes of exemplification since in 90 actual practice it attains the features of advantage enumerated as desirable in the statement of the invention and the above description.

It will be apparent that changes in the details of construction, and in the combination and arrangement of parts may be resorted to 95 without departing from the spirit or scope of the invention as hereinafter claimed or sacrificing any of its advantages. 100

Having thus described my invention, what I claim as new is:

- 5 1. An apparatus of the class described including a plurality of sections, each section comprising a hood, blocks in the hood, a shaft journaled in the blocks, a plurality of blades, means for attaching the blades to the shaft so that they may swing laterally, levers on the shaft for rocking the same.
- 10 2. An apparatus of the class described including a plurality of sections, each section comprising a hood, blocks in the hood, a shaft journaled in the blocks, a plurality of blades, means for attaching the blades to the shaft so that they may swing laterally, levers on the shaft for rocking the same, hook plates at the ends of the hoods having hooks at their rear ends and eyes at their forward end, and links engaged in the eyes to engage with the hooks.
- 15 3. An apparatus of the class described including a plurality of sections, each section comprising a hood, blocks in the hood, a shaft rockable in the block, means for rocking the shaft, U-shaped members circumjacent the shaft to extend rearwardly therefrom, brackets pivotally mounted between the extremities of the U-shaped members to rock on an axis at right angles to the axis of the shaft, and blades fixed to the bracket.
- 20 4. An apparatus of the class described including a plurality of sections, each section comprising a hood, blocks in the hood, a shaft rockable in the block, means for rocking the shaft, U-shaped members circumjacent the shaft to extend rearwardly therefrom, brackets pivotally mounted between the extremities of the U-shaped members to rock on an axis at right angles to the axis of the shaft, and blades fixed to the bracket, hook plates at the ends of the hoods terminating at their forward ends in eyes and at their rear ends in hooks, links engaged with the eyes to detachably engage with the hooks.
- 25 5. A section for the apparatus described including an elongated hood of U-shaped formation in cross section with its bight disposed forwardly and its upper leg wider than its lower leg, blocks fixed in the ends of the hood, a shaft journaled in the block, U-shaped members circumjacent the shaft and fixed thereto so that the legs extend rearwardly, a bracket pivotally mounted between the extremities of the U-shaped members to rock on an axis at right angles to the axis of the shaft, a blade rigidly attached to each bracket.
- 30 6. A section for the apparatus described including an elongated hood of U-shaped formation in cross section with its bight disposed forwardly and its upper leg wider than its lower leg, blocks fixed in the ends of the hood, a shaft journaled in the block, U-shaped members circumjacent the shaft and fixed thereto so that the legs extend rearwardly, a bracket pivotally mounted between

the extremities of the U-shaped members to rock on an axis at right angles to the axis of the shaft, a blade rigidly attached to each bracket, levers fixed to the shaft, notched segments on the hood, detent structures on the levers for association with the notched segments.

In testimony whereof I affix my signature.
CHARLES E. SAYRE.
